DESIGN FOR LACE

Edward E. Bancroft, West Warwick, R. I., assignor to Acme Textiles Co. Inc., New York, N. Y., a corporation of New York

Application February 11, 1936, Serial No. 61,092

Term of patent 3½ years

To all whom it may concern:

Be it known that I, Edward E. Bancroft, a citizen of the United States, residing at West Warwick, in the county of Warwick and State of Rhode Island, have invented a new, original, and ornamental Design for Lace, of which the following is a specification, reference being made to the accompanying drawing, forming a part thereof.

The figure is a plan view of a piece of lace embodying my design.

The area disclosing the design in detail constitutes the design unit and the area shown in full lines continues in the relation indicated beyond the unit boundaries.

I claim:

The ornamental design for lace substantially as shown and described.

EDWARD E. BANCROFT.
